DOUBLE APRON DRAWING ARRANGEMENT FOR SPINNING MACHINES

Adolf Schiltknecht, Winterthur, and Fernand Cousin, Chippis, Switzerland, assignors to Joh. Jacob Rieter & Co. Ltd., Winterthur, Switzerland, a corporation of Switzerland

Filed June 25, 1958, Ser. No. 744,370

Claims priority, application Switzerland June 29, 1957

10 Claims. (Cl. 19—131)

The present invention relates to a double apron drawing arrangement for spinning machines and more particularly to adjustable means for guiding and reversing the lower apron of such arrangements.

In conventional double apron drawing arrangements for spinning machines the retainment of the sliver is adjusted by changing the pressure acting on the sliver or by changing the curvature of a guide surface which is connected with or forms part of the reversal bar for the lower apron in order to answer different requirements depending on the number of the roving, the staple diagram, the draft, the kind of the fibre, the spreading of the sliver, and the like. Also used are eccentric cams and transverse rods movable adjacent to the inside surface of the aprons and in the direction of the movement of the sliver.

The ideal force acting on the sliver, i.e., the ideal distribution of the pressure is most nearly obtained, if the curvature of the bridge or bar acting on the aprons can be continuously, i.e., not stepwisely adjusted and retained in the optimal condition. Such adjustment takes time. Interchangeable reversing bars having different profiles have been used to facilitate the adjustment. Keeping an adequate supply of these bars is costly.

The object of the present invention is to provide a reversing bar arrangement for the lower apron of double apron drafting arrangements for spinning machines in which only one bar can satisfy a great number of different drawing conditions. The bar according to the invention has a plurality of differently shaped surface portions which are selectively engageable by the lower apron. The bar and its support are provided with complementary means affording fixing of the bar in different positions so that a selected one of its surface portions engages and guides the apron.

For machines in which bearing notches are already present in the drawing roller supports which notches are not coaxial with the reversal bars, the invention provides adaptors individually having a portion resting in one of the existing notches. The adaptors have means located symmetrically with respect to the longitudinal axis of the reversal bar and adapted to engage complementary means associated with the reversal bar. This structure permits connection of the reversal bar and of the adaptor in different relative angular positions.

The novel features which are considered characteristic of the invention are set forth with particularity in the appended claims. The invention itself, however, and additional objects and advantages thereof will best be understood from the following description of embodiments thereof when read in connection with the accompanying drawing, in which:

Fig. 1 is a diagrammatic side view of a double apron drawing arrangement including an adjustable bar according to the invention for guiding the lower apron.

Fig. 2 shows a portion of Fig. 1 with the adjustable bar in a different position.

Fig. 3 shows a portion of Fig. 1 with the adjustable bar in a third position.

2

Fig. 4 shows a portion of Fig. 1 with the adjustable bar in a fourth position.

Fig. 5 is a diagrammatic side view of a guide bar according to the invention.

Fig. 6 is a diagrammatic cross sectional view of a modified arrangement for adjustably supporting a guide bar.

Fig. 7 is a diagrammatic side view of the arrangement shown in Fig. 6 with the drawing roller support removed.

Fig. 8 is an end view of a guide bar and of an intermediate element according to the invention for angularly adjustably supporting the guide bar.

Fig. 9 is a diagrammatic part sectional view of the device shown in Fig. 8, the section being taken along line IX—IX in Fig. 8, a roller support being added.

Fig. 10 is a perspective end view of the guide bar and intermediate element shown in Fig. 8.

Referring more particularly to Fig. 1 of the drawing, numerals 2, 3, 4 designate drawing roller supports mounted and secured on a roller stand in the conventional manner. Drawing rollers 8, 9 and 10 rotatably rest in suitable recesses 5, 6 and 7 of the supports 2, 3, 4, respectively. Loaded top rollers 11, 12 and 13, which may be guided at their ends or in their middle portions, rest on the drawing rollers 8, 9 and 10. The roller 12 which is 20 between the rollers 11 and 13 carries a conventional guide cradle 14 which guides a top apron 15 laid around the cradle so that the top apron moves along a lower apron 16 to the nip of the delivery rollers 8 and 11. The lower apron 16 is tensioned in known manner by conventional 25 tensioning devices, not shown, which are located below the run of the lower apron 16 which run is adjacent to the upper apron. The lower apron 16 is first guided by and subsequently turned around a reversing bridge or bar 30 17 having a generally prismatic configuration, the individual surfaces 40, 41, 42 of the bar 17 having different configurations. The surface 40 is plane, the surface 41 uniformly convexly curved and the surface 42 has a slightly curved major portion and a minor portion close to an edge of the bar, the minor portion having a more pronounced convex curvature. Each end of the bar 17 is provided with a short equilateral prismatic coaxial 35 protuberance 18 which rests in a complementary notch 19 of the support 2. The thickness of the latter is preferably twice the longitudinal extension of the protuberance 18 so that the protuberances of two axially aligned bores 40 can be received in the same notch. The bar 17 can easily 40 be lifted out of the notch 19, turned 120° on its longitudinal axis and reinserted in the notch for changing the curvature on which the lower apron is guided to comply 45 with different drawing requirements. Figs. 2 and 3 illustrate two different operating conditions of the bar 17 which can be obtained by clockwise turning the bar on its longitudinal axis.

By turning the bar 180° from the position shown in 50 Fig. 2 in a plane which is parallel to the drafting field and on an axis which is normal to the longitudinal axis of the bar, as indicated in Fig. 5, an additional position, shown in Fig. 4, can be obtained and two further positions can be obtained by turning the bar on its longitudinal axis 55 from the position shown in Fig. 4. With a generally prismatic bar 17 six different operating positions can be obtained. Experience has shown that six different operating 60 positions are generally sufficient to cope with any drawing requirement. If desired, the bar may be provided with a quadratic cross section to increase the number of 65 surfaces to four. The bar can be provided with a polygonal cross section having more than four corners to further increase the number of different surfaces from which a desired surface can be selected. The bar may also be 70 so modified that it has only two different operating surfaces.

Figs. 6 and 7 illustrate a modified embodiment of the

invention. A holder 20 is mounted by means of screws on the drawing roller support or bearing 2. The central portion of the holder 20 is provided with a vertical slot 21 slidably receiving a rail 22, the top of which forms a clamping member 23. The member 23 is provided with a bore 24, continuing in a slot 25. In the bore 24 a short pin 26 is received which pin extends axially from an end of a reversing bridge or bar 17'. The diameter of the pin 26 is so that the pin must be forced into the bore 24 whereby the prongs formed on the member 23 by the bore 24 and the slot 25 are slightly pressed apart so that the pin 26 is retained in any desired angular position by a clamping effect in contradistinction to the arrangement shown in Figs. 1 to 5 in which the bar 17 can be held only in three different angular positions. The arrow 43 in Fig. 7 indicates the rotatability of the bar 17' in opposite directions. By inserting shims 27 of suitable thickness between the holder 20 and the clamping head 23 the position of the bar 17' can be vertically adjusted as indicated by arrows 44 in Fig. 7. The shims 27 are held in place by the end of the bar 17'.

Figs. 8, 9 and 10 illustrate a further embodiment of the invention. The end of the bridge member or bar 28 is provided with a short axial bore 29. Three bores 31 extend from the bottom 30 of the cavity formed by the bore 29 into the bar 28. The bores 31 are arranged on a circle whose center is in the longitudinal axis of the bore 29. The bores 31 are angularly spaced by 120°.

The bar 28 is supported by an intermediate piece 32 having a cylindrical portion 34 fitting into the bore 29 and a protuberance 36 extending in axial direction from the cylindrical portion 34 and into a recess 35 in the support 2 which recess is nonsymmetric with respect to the longitudinal axis of the bar 28. A rodlike protuberance 37 extends from the portion 34 in a direction which is opposite to the extension of the protuberance 36. For changing the angular position of the bar 28 the bar with the intermediate piece 32 is taken out of the recess 35 whereupon the intermediate piece 32 is pulled out of the bar 28 and rotated for insertion of the rodlike protuberance 37 in a desired one of the bores 31. After this has been done the assembly is again inserted in the recess 35 of the drawing roller support. The modification illustrated in Figs. 8 to 10 is particularly suitable in connection with machines which already have notches or recesses which are not suitable for using the embodiments of the invention shown in Figs. 1 to 7. The modification shown in Figs. 8 to 10 is also suitable for adapting machines which initially did not have rotatable reversing bars to the use of adjustable reversing bars according to the invention.

What is claimed is:

1. In a double apron drawing arrangement for spinning machines, a lower apron in the form of an endless belt having an upper run supporting the textile fibres, a guide bar placed beneath said upper run and having a plurality of reversing edges and a differently shaped guide surface portion extending from each of said reversing edges for guiding a substantial portion of said upper run, and support means for said guide bar, said guide bar and said support means including cooperating means for selectively placing said guide bar in a position in which a selected one of said guide surface portions is adjacent to and guides a substantial part of said upper run according to the shape of the respective guide surface.

2. In a double apron drawing arrangement as defined in claim 1 and wherein said bar is rotatable on its longi-

tudinal axis and said surface portions are parallel to the longitudinal axis of the bar.

3. In a double apron drawing arrangement as defined in claim 1 and wherein said bar rests on said support means and is liftable therefrom for swinging said bar 180° in a plane parallel to the drafting field and on an axis which is normal to the longitudinal axis of the bar for changing the operating positions of the individual surface portions.

4. In a double apron drawing arrangement according to claim 2 and wherein said cooperating means include complementary holding means engageable one by the other for holding said bar in selected angular positions.

5. In a double apron drawing arrangement according to claim 4 and wherein said complementary holding means are provided with plane surfaces parallel to the longitudinal axis of the bar and placed at an angle to each other for stepwisely changing the angular position of said bar.

6. In a double apron drawing arrangement according to claim 4 and wherein said holding means provided on said bar are in the form of equilateral prisms and said holding means provided on said support means are in the form of triangular notches individually receiving said prisms, said bar having the general configuration of a prism whose longitudinal surfaces are individually parallel to the surfaces of the holding means provided on said bar.

7. In a double apron drawing arrangement according to claim 4 and wherein said complementary holding means are provided with cylindrical surfaces coaxial of the longitudinal axis of the bar and frictionally engaging one another for continuously changing the angular position of said bar.

8. In a double apron drawing arrangement according to claim 7 and wherein the holding means on said bar are cylindrical and coaxial of said bar and the holding means on said support means are in the form of clamps clamping the cylindrical holding means on said bar in a direction normal to the longitudinal axis of the bar.

9. In a double apron drawing arrangement as defined in claim 1 and wherein said cooperating means include means for changing the position of said bar relatively to the drafting field.

10. In a double apron drawing arrangement for spinning machines, a lower apron in the form of an endless belt having an upper run supporting the textile fibres, a guide bar placed beneath said upper run and having a plurality of reversing edges and a differently shaped guide surface portion extending from each of said reversing edges for guiding a substantial portion of said upper run, support means, and an element having a part resting on said support means and having a portion engageable with said guide bar for supporting said guide bar, said guide bar having a plurality of means individually complementary to said portion on said element for individually engaging said last mentioned portion, said complementary means being arranged symmetrically around the longitudinal axis of said guide bar for changing the relative angular position of said guide bar and said element.
